(57) **CLAIM**

The ornamental design for an electronic housing, as shown and described.

DESCRIPTION

FIG. 1 shows a perspective view of an electronic housing.

FIG. 2 shows a front view of the electronic housing.

FIG. 3 shows a back view of the electronic housing.

FIG. 4 shows a right side view of the electronic housing.

FIG. 5 shows a left side view of the electronic housing.

FIG. 6 shows a top view of the electronic housing; and,

FIG. 7 shows a bottom view of the electronic housing.

The broken lines in the drawings illustrate portions of the electronic housing which form no part of the claimed design.
